Attorney.

UNITED STATES PATENT OFFICE.

HARRY J. HICK, OF ALLIANCE, OHIO, ASSIGNOR TO THE McCASKEY REGISTER COMPANY, (INCORPORATED IN 1914,) OF ALLIANCE, OHIO, A CORPORATION OF OHIO.

HINGE FOR FILING-APPLIANCE CASES.

1,253,376.

Specification of Letters Patent. Patented Jan. 15, 1918.

Application filed August 5, 1914. Serial No. 855,231.

To all whom it may concern:

Be it known that I, HARRY J. HICK, a citizen of the United States, residing at Alliance, in the county of Stark and State 5 of Ohio, have invented certain new and useful Improvements in Hinges for Filing- Appliance Cases, of which the following is a specification.

The invention relates to a case for a filing 10 appliance, which may include a series of hinged holders operatively mounted therein and adapted to be completely inclosed by the case for protection against fire and like damage.

The invention contemplates the use of a 15 rectangular case composed of a lower or base section and an upper or cover section, with guiding hinge connections between the sections, so that the upper section can be closed 20 downward upon the base section to completely incase the bill holders mounted therein, or can be swung upward with its rear end resting upon the rear portion of the base section to form a back or support for 25 the bill holders in operative position.

In a former application, filed June 1, 1914, Serial No. 841,976, a filing appliance of this 30 type or character has been illustrated, described and claimed, in which similar base and cover sections are provided with inter- meshing tongues and grooves upon the side and forward rims and rabbets upon the rear 35 rims, and with guiding hinge connections between their rear ends for swinging and shifting the cover sections upon the base sections, so that when closed the rear ends will be in alinement, and when open, the top of the cover section will be alined with the rear end of the base section.

40 And in a subsequent application filed July 27, 1914, Serial No. 853,254, a modified form of filing appliance case is illustrated, described and claimed, in which similar base and cover sections are provided with inter- 45 meshing tongues and grooves upon the rear rim as well as the side and forward rims, together with improved guiding hinge connections between the case sections for caus- 50 ing a clearance of the tongues and grooves on the rear rims during the operation of the cover section upon the base section.

The object of the present improvement is to provide a simple construction and ar- 55 arrangement of the guiding hinge connections, which will permit the use of intermeshing

rabbets on all sides and ends of the case sections.

This object is attained by downwardly offsetting the rear ends of the horizontal guide- 60 ways in the hinge connections so that the rear rims will be cammed and clamped together thereby. A preferred embodiment of the invention is illustrated in the accom- 65 panying drawings, forming part hereof, in which—

Figure 1 is a side elevation of the im- 70 proved filing appliance case with the cover section closed upon the base section, showing the improved guiding hinge connection, partly in section to expose details of con- struction; and

Fig. 2, a section of the case, showing the 75 cover section swung into upright position upon the base section, with a series of bill holders mounted therein, the case sections being provided with rabbeted rims.

Similar numerals refer to similar parts throughout the drawings.

The case is composed of the substantially 80 similar rectangular bottom or base section 1 and the top or cover section 2, which are operatively connected together by means of the guiding hinge brackets 3, one being located on each side of the rear end portion 85 of the case.

The guiding hinge brackets 3 are secured 90 by the depending flanges 13 thereon to the sides of the base section at the rear end thereof, as by means of the bolts 14; the upper ends of which securing flanges are offset to form the horizontal tracks 15 sub- 95 substantially in the same plane with the side rims of the base section. The ends of each track 15 are curved first upward and then inward a short distance above and parallel with the track to form the horizontal guide 16 located above the track, thereby forming the straight horizontal way 17 between the track and the guide.

The vertical guide flanges 18 are provided 100 in the upper portion of each bracket above the middle portion of the horizontal way, between which guides is formed the straight vertical way 19. The sliding pivot posts 20 are provided on the lower rear side corners 105 of the cover section of the case, and as shown may be in the form of rollers journaled thereto, which rollers are adapted to travel in the horizontal ways upon the horizontal tracks of the brackets; and the sliding pivot 110

rollers 21 are journaled on the sides of the cover section substantially equidistant from the upper and rear edges thereof, which rollers are adapted to travel in the vertical ways between the vertical guides of the brackets.

By these connections it is evident that the cover section of the case may be swung and completely shifted upon the base section thereof so that when the cover section is in upright position, its top wall will align with the rear wall of the base section. For the purpose of the present invention the rear ends of the horizontal tracks 15 and guides 16 are downwardly offset, thus likewise 10 downwardly offsetting the rear ends of the horizontal ways 17; and it is evident that when the pivotal rollers 20 ride rearward toward and into the rear ends of these ways, during the final closing movement of the 15 cover section upon the base section, the rear rim of the cover section will be cammed and clamped downward upon the rear rim of the base section, thereby securely sealing the joint formed thereby.

20 25 I claim:

1. A filing case including similar base and cover sections with guiding hinge connections between the rear ends for swinging and completely shifting the cover section 30 upon the base section, and cam devices in the hinge connections for drawing and clamping the rear rims together.

2. A filing case including similar base and cover sections with guiding hinge connections between the rear ends for swinging and 35 shifting the cover section upon the base section, the guiding hinge connections having horizontal guide-ways with downwardly offset rear ends on the base section and pivots 40 on the cover section operating in the guide-ways for clamping the rear rims together

during the final closing movement only of the case sections.

3. A filing appliance including a case composed of a base section having side bottom and rear walls and a cover section having side top and rear walls, and guiding hinge connections between the rear ends of the sections for swinging and shifting the cover section upon the base section with the 45 rear wall of the cover section in alinement with the rear wall of the base section, said connections comprising brackets on the base section having straight horizontal and vertical ways and pivots on the cover section operating in the ways, the pivots operating in the vertical ways being spaced substantially equidistant from the top and rear walls of the cover section.

4. A filing appliance including a case 60 composed of a base section having side bottom and rear walls and the cover section having side top and rear walls, and guiding hinge connections between the rear ends of the sections for swinging and shifting the 65 cover section upon the base section with the rear wall of the cover section in alinement with the rear wall of the base section, said connections comprising brackets on the base section having straight horizontal and vertical ways and pivots on the cover section operating in the ways, the pivots operating in the vertical ways being spaced substantially equidistant from the top and rear walls of the cover section and there being cam devices at the ends of the horizontal ways for drawing and clamping the rear rims together.

70 75 76 HARRY J. HICK.
